SPRING ASSEMBLY

Edward E. Woller, Kenosha, Wis., assignor to
Simmons Company, New York, N. Y., a corpora-
tion of Delaware

Application May 7, 1949, Serial No. 91,889

4 Claims. (Cl. 5—353)

1

This invention relates to the construction of a series of pockets in superimposed layers of fabric, each of which pockets encases a spring coil and sections of which pocket-encased springs are arranged side by side to form mattresses or cushions of the so-called Marshall type. Lengths or sections of these pocket-encased springs are generally secured side by side with the spring axes parallel to provide a mattress or a cushion of the desired proportions. These sections are generally formed by inserting the compressed spring coils into folded-over fabric which is stitched along one lateral edge and transversely between the spring coils. After the stitching, the spring coils are released and adjusted in each of the pockets. After assembling sections of pocketed springs into a mattress, the springs of alternate rows, as a rule, are tied together by cords looped over the end convolutions of the springs and extend transversely across the mattress or cushion from the border section or length on one side to that on the other.

Because the transverse stitching, which forms the pockets, in these superimposed fabric layers, extends entirely across the strip, adjacent pockets are attached throughout their entire length. Hence, under certain conditions, the local depression of any one spring has a tendency to exert an undesirable side pull upon the springs on opposite sides of the depressed spring.

The main object of this invention is to provide an improved construction of mattresses or cushions of the inner-spring type which permits any spring to be depressed a material distance without undesirably disturbing the adjacent springs.

In the accompanying drawings:

Fig. 1 is a partly sectional and partly end elevation of a Marshall-type mattress, the interior of which is composed of fabric-pocketed coils embodying this invention;

Fig. 2 is an enlarged, fragmentary, elevational view of a section of a preferred form of pocket construction embodying this invention;

Fig. 3 is a transverse sectional view of the same, taken on the line 3—3 of Fig. 2;

Fig. 4 is a view, similar to Fig. 2, of a modified form of pocket construction embodying this invention;

Fig. 5 is a transverse, sectional view taken on the line 5—5 of Fig. 4;

Fig. 6 is a diagrammatic perspective view of a section of folded fabric wherein the transverse stitching for forming the pockets embodies the preferred form of this invention;

2

Fig. 7 is a similar view wherein the transverse stitching embodies a modified form of this invention;

Fig. 8 is a plan view of a fragment of the assembled pocketed springs showing the manner in which alternate springs are tied together transversely of the spring-encased sections which form the mattress shown in Fig. 1; and

Fig. 9 is an enlarged transverse sectional detail taken on the line 9—9 of Fig. 8.

Mattress- or cushion-forming sections of pocketed springs, embodying this invention, comprise superimposed layers or plies of fabric 10 stitched together to form pockets 11, in each of which pockets is encased a spring coil 12 and between which pockets the fabric 10 is severed, as shown at 13, a predetermined distance inwardly from each lateral edge. The stitching of the fabric 10 and the forming, insertion, and ultimate positioning of the spring coils 12 in the pockets 11 is effected on a machine of the type shown in Patent No. 1,813,993, altered, of course, to secure the form of stitching and slitting embodying this invention.

The fabric 10 is usually cotton sheeting. A strip of such fabric, after being folded upon itself to provide superimposed layers, is stitched at 14 along one lateral edge and at 15 at transverse intervals to form the pockets 11 (see Fig. 4).

The spring coils 12 are preferably of the "barrel" type construction, as clearly shown in the drawings. Accordingly, the end convolutions are slightly smaller in diameter than the intermediate convolutions. For this reason, there is slightly more fabric between contiguous pockets 11 adjacent the lateral portions of the fabric than is provided with the "cylindrical" type of springs.

In a construction embodying the preferred form of this invention, there is a double line of the transverse stitching 15, as most clearly shown in Figs. 2, 3, and 6. Such parallel stitching results in the formation of narrow strips 16 of fabric between the parallel lines of stitching 15 intermediate each of the pockets 11.

In the modified form, as best shown in Figs. 4, 5, and 7, there is but a single line or row of transverse stitching 15 extending entirely across the strip and separating the adjacent pockets 11. However, a second line 17 of transverse stitching is extended a predetermined distance inwardly from the opposite lateral edges of the fabric adjacent and substantially parallel to the single line 15 of the stitches. This results in the formation of a narrow strip 16' of fabric between con-

tiguous springs 12 only adjacent the lateral edges of the strip 10.

Between these transverse parallel lines of stitches the strip 16 or 16' of fabric is cut, as shown at 13, Figs. 2, 4, 6, and 7. This severs all direct connection between the pockets 11 for some distance inwardly from the opposite lateral edges of the fabric 10. Accordingly, each of the spring coils 12 may be individually depressed a substantial distance without causing any material displacement of the spring coils on either side of the depressed coil. For that reason the ends of the coils directly contiguous to a depressed coil will not be disturbed but will remain horizontally-disposed until the force causing the depression of a spring coil has moved its end inwardly of the inner terminus of the slits 13.

The transversely extending lines of stitching 15 in the preferred form of the invention, and the lines 15 and 17 in the modified form, are preferably disposed as close to one another as is practicable to permit the strips 16 and 16' to be slit without opening the adjacent pockets. Furthermore, the size of the barrel-shaped spring coils 12 relative to the pockets is desirably such that the pocket forming strips tautly enclose the coils and tend to assume the outline of the latter, the fabric being drawn inwardly between the convolutions, as is clearly shown in Figures 1, 2, 4 and 9. As a result of this stretching of the pocket-forming strips, the inter-pocket connecting strip 16 of the preferred form is deformed, as is the single transversely extending line of stitching in the modified form of the invention, so that in both forms of the invention the intermediate convolutions of the adjacent barrel-shaped coils intermesh (see Figures 2 and 4) while the end convolutions remain spaced apart. With this arrangement, adjacent coils in a single row or series are flexibly yet compactly associated, and yet the independent coil action permitted by partial severance of the pocket-forming strips between the coils, is not impaired. These spring coil series are capable of being closely assembled, as will subsequently appear, with like series or rows to form a dense and compact spring assembly.

Sections or lengths of these fabric-pocketed spring coils are arranged side by side in staggered rows in the manner indicated in Fig. 8, so that the intermediate convolutions of any one spring coil intermesh with the intermediate convolutions of the two adjacent coils in the rows or sections on either side. However, the end convolutions of juxtaposed coils in adjacent rows, like adjacent coils in a single row or section, remain spaced apart to retain their individual freedom of action. The assembled sections ultimately are surrounded, top, bottom, and sides, with the usual layers of tufted padding 18, as most clearly shown in Fig. 1. Before the padding is put on, the end convolutions of certain of the alternate spring coils 12 are connected by ties 19, these ties being spaced at suitable intervals along the rows. Such a tie is generally in the form of a cord. As indicated at 20, Fig. 8, one end of a tie 19 is knotted around an end convolution of each of the coils along one lateral edge of the assembly and extended across the mattress transversely to the row of pocketed coils along the opposite lateral edge of the assembly. The tie is looped around the end convolution of each coil in the alternate intermediate sections parallel to the lateral edges, as indicated at 21, Fig. 8. At the opposite edge of the assembly the ties 19 are

knotted around the end convolutions of the opposite lateral row of coils.

Variations and modifications in the details of structure and arrangement of the parts may be resorted to within the spirit and coverage of the appended claims.

I claim:

1. A connected series of fabric-pocketed spring coils for mattress formation comprising a strip 10 of textile fabric formed of two fabric plies, one overlying the other, said strip having parallel longitudinal edges, said plies being connected together along both of said longitudinal edges, at least one of said connections comprising stitching 15 extending along and adjacent to one edge of said strip, equally spaced, parallel lines of stitching extending transversely across said strip and connecting said plies at spaced intervals thereby forming a series of contiguous pockets between said plies, other lines of stitching extending inwardly from each of said edges a predetermined distance and substantially parallel to and closely adjacent to said spaced parallel lines of stitching, and a spring coil on each of said pockets, 25 said coils having intermediate convolutions of greater diameter than the end convolutions and being of sufficient size to deform said pockets to draw the walls thereof inwardly between the convolutions, the intermediate convolutions of the 30 spring in each pocket intermeshing with the intermediate convolutions of the springs in the immediately adjacent pockets while the end convolutions of the springs remain spaced apart, said strip having a series of equally spaced slits extending from each edge inwardly for a limited 35 distance, the space between each of said other lines of stitching and the adjacent one of said spaced parallel transverse lines of stitching having one of said slits extending into such space.
- 40 2. A connected series of fabric-pocketed spring coils for mattress formation comprising a strip of textile fabric formed of two fabric plies, one overlying the other, said strip having parallel longitudinal edges, said plies being connected together along both of said longitudinal edges, at least one of said connections comprising stitching 45 extending along and adjacent to one edge of said strip, equally spaced pairs of parallel lines of stitching extending transversely across said strip and connecting said plies at spaced intervals to form a series of contiguous pockets between said plies, and a spring coil in each of said pockets, said coils having intermediate convolutions of greater diameter than the end convolutions and being of sufficient size to deform said pockets to draw the walls thereof inwardly between the convolutions, the intermediate convolutions of the spring in each pocket intermeshing with the intermediate convolutions of the springs in the immediately adjacent pockets while the end convolutions of the springs remain spaced apart, said strip having a series of equally spaced slits extending from each edge inwardly for a limited 55 distance, the space between the lines of each of said pairs having one of said slits extending from each edge into such space.
- 50 3. A connected series of fabric-pocketed spring coils for mattress formation comprising a strip of textile fabric formed of two fabric plies, one overlying the other, said strip having parallel longitudinal edges, said plies being connected together along both of said longitudinal edges, at least one of said connections comprising stitching 55 extending along and adjacent to one edge of said strip, parallel lines of stitching extending

transversely across said strip and connecting said plies at spaced intervals to form a series of contiguous pockets of equal width between said plies, and a spring coil in each of said pockets, said coils having intermediate convolutions of greater diameter than the end convolutions and being of sufficient size to deform said pockets to draw the walls thereof inwardly between the convolutions, the intermediate convolutions of the spring in each pocket intermeshing with the intermediate convolutions of the springs in the immediately adjacent pockets while the end convolutions of the springs remain spaced apart, alternate rows being connected together at intervals disposed longitudinally thereof, and said strip having a series of equally spaced slits, said slits extending inwardly from each edge adjacent to, and slightly beyond the extremity of, one of said parallel lines of stitching.

4. A spring assembly for the formation of mattresses and the like, comprising juxtaposed rows of fabric-pocketed spring coils, each of said rows comprising a length of textile fabric strip formed of two fabric plies, one overlying the other, said strip having parallel longitudinal edges, said plies being connected together along both of said longitudinal edges, at least one of said connections comprising stitching extending along and adjacent to one edge of said strip, spaced parallel lines of stitching extending transversely across said strip and connecting said plies together at spaced

intervals to form a series of contiguous pockets of equal width between said plies, and a spring coil in each of said pockets, said coils having intermediate convolutions of greater diameter than the end convolutions and being of sufficient size to deform said pockets to draw the walls thereof inwardly between the convolutions, the intermediate convolutions of the spring in each pocket intermeshing with the intermediate convolution of the springs in the immediately adjacent pockets while the end convolutions of the springs remain spaced apart, alternate rows being connected together at intervals disposed longitudinally thereof, and said strip having a series of equally spaced slits, said slits extending inwardly from each edge adjacent to, and slightly beyond the extremity of, one of said parallel lines of stitching.
